INKING MECHANISM FOR PRINTING
PRESSESCharles F. Root, Cleveland, Ohio, assignor to The
Chandler & Price Company, Cleveland, Ohio, a
corporation of Ohio

Application March 10, 1945, Serial No. 582,012

13 Claims. (Cl. 101—342)

1

The present improvements, relating as indicated to inking mechanism for printing presses, have more particular regard to inking mechanism for platen printing presses of the so-called Gordon type. It will be understood, however, that the several improvements which constitute the invention may be advantageously used with printing presses of other types, where a form requires to be inked by transfer of ink from a suitable fountain or like source spaced from such form.

In such presses the ink is customarily transferred from the fountain onto a distributing disc or plate by means of rollers which travel back and forth across the latter, and the ink is then in turn transferred from such disc or plate onto the form by the same or a second similar set of rollers. In the first of these operations, one of the difficulties encountered is that the rollers which transfer the ink from the fountain naturally tend to deposit more of such ink on the portion of the distributing disc or plate with which they first come into contact, and even though provision is made for rotation of the disc or plate between passes of such rollers, the distribution of ink on the surface is apt to remain uneven. Accordingly, when the form rollers in turn take up the ink from the disc they are apt to receive an uneven coating and this will obviously lead to the non-uniform inking of the form.

In my pending application filed April 8, 1943, Serial No. 482,230, now Patent No. 2,377,269, I disclose a method of and apparatus for distributing ink onto a shiftable plate such as the rotatable disc just referred to which comprises passing the ink-bearing rollers back and forth across and in contact with such plate except for a portion of such passage during which said plate is left free to be shifted. In the specific embodiment shown and described in said application the means for effecting operation as stated are designed automatically to raise the inking rollers out of contact with the plate during an intermediate portion of their movement across the latter. I have now discovered that such operative effect may be more advantageously obtained by automatically raising and lowering the disc so as to prevent contact of the rollers therewith during a portion of their movement. Not only is this arrangement a simple one which may be more readily incorporated in presses of the type in question, but the action can be made more certain and positive and at the same time regulation of the period of non-contact of the rollers with the disc or plate is easily secured.

2

To the accomplishment of the foregoing and related ends, said invention, then, consists of the means hereinafter fully described and particularly pointed out in the claims.

5 The annexed drawings and the following description set forth in detail certain mechanism embodying the invention, such disclosed means constituting, however, but one of various mechanical forms in which the principle of the invention may be used.

In said annexed drawings:

Fig. 1 is a side elevation of a printing press of the Gordon type, only such portions thereof other than the form-carrying bed and associated inking mechanism being shown as are necessary to an understanding of the present improvements;

Fig. 2 is a side elevation on a larger scale, and with certain parts shown in vertical section, of the inking disc and associated parts which constitute one embodiment of the invention;

Fig. 3 is a top plan view of certain of such parts;

Figs. 4 and 5 are views similar to Fig. 2, respectively showing the parts of present interest in different operative positions;

25 Fig. 6 illustrates in section a detail of the foregoing on a larger scale; and

Figs. 7, 8, 9 and 10 are likewise views similar to that of Fig. 2, but respectively showing other embodiments of the invention.

30 Referring to the general view of the press shown in Fig. 1, the bed 1 of the press, in the face of which the form (not shown) is secured in familiar manner, is oscillatorily supported at its lower end about an axis 2 in the main frame 3 of the press. Oscillation of bed 1 is produced by means of connecting rods or side arms 4, one on each side, which are attached at one end to cranks 5 on a rotating part of the press and at the other to the corresponding ends of a shaft 6 that extends transversely through the bed. The last-named connections include eccentrics by oscillation of which the bed may be displaced sufficiently so as to prevent the form from coming into contact with the platen (not shown), such shifting of the eccentric connections just referred to being effected by the usual means such as hand lever 7 and interconnected system of links and levers 8 and 9.

Also oscillatorily mounted on shaft 6 are roller frames 10, one on each side of the bed, which carry the form inking rollers 11, shown as consisting of two pair, which are mounted in the usual manner in the forward portion of said frames. Oscillation of arms 10 is likewise produced in the usual manner by means of a link

12 connected at one end with a pivot 13 spaced from the axis of oscillation of the arms and at the other to a fixed point 14 on the main frame of the press.

Mounted on a bracket 15 that projects upwardly from bed 1 is an ink distributing plate 16, which is preferably in the form of a disc, as shown, such disc being formed on its under side with a central stud 17 whereby it is rotatably supported in a suitable bearing formed in the upper end of bracket 15. An ink fountain 20 is located beyond the upper end of the ink distributing disc, such fountain including a roller 21 which in its normal position is adapted to contact with one or both of two ink distributing rollers 22, that together with a vibrating roller 23, are supported in suitable trucks or saddles 24 so as to be movable up and down across the face of the disc. Such trucks or saddles form part of a carriage which consists of side frames 25, of reversed C-form, the lower portions whereof are provided with spaced rollers 26 that travel in outwardly facing channel guideways 27.

Reciprocable movement of the carriage and of the ink distributing rollers thus carried thereby is derived from oscillation of one of the side arms 10 by means of a link 28 connected at one end to a lower portion of the corresponding side frame of the carriage at a point intermediate of rollers 26 and at the other end to a boss 29 on such side frame. Rollers 22 are provided with truck wheels on their respective ends which are adapted to run on tracks 30 disposed in parallel relation, one on each side of disc 16, these tracks being joined by curved sections 31 with other tracks 32 that are similarly disposed alongside the face of bed 1 in which the form is secured. There is thus formed a continuous truckway from a point adjacent the upper or rear edge of the disc to a point lying below the lower edge of such form, so that form rollers 11 may travel upwardly along such truckway and across the ink distributing disc 16 after a film of ink has been transferred thereto by the distributing rollers 22.

To assist in the even distribution of ink on the disc by rollers 22, means are provided for imparting to such disc a step-by-step rotative movement. Any suitable means may be employed for this purpose, those illustrated being substantially as shown and described in Patent No. 2,079,172 to L. R. Johnson et al., dated May 4, 1937. For the present purpose it will be sufficient to note that such illustrated means comprise a downwardly facing bevel gear 35 secured onto the lower end 36 of stub shaft 17 which projects through the bearing wherein such shaft is mounted, and two bevel gears 37 mounted on a transverse shaft 38 located directly below such bearing (see Figs. 2 and 3.) Said last-named gears are shiftable on the shaft 38 to bring either one into engagement with gear 35 as desired and by thereupon imparting rotative movement to such engaging gear the disc may be rotated in either a clockwise or counterclockwise direction and through such an arc as may be required for the particular operation.

Referring to the first embodiment of the invention, as illustrated in detail in Figs. 2 to 5 inc., it will be noted that the stub shaft 17 whereby disc 16 is thus rotatably supported is somewhat longer than the bearing in bracket 15 so as to be also capable of axial shifting movement in such bearing. While normally under the influence of gravity said shaft would assume its lowermost position, as shown in Fig. 5, it is normally raised.

slightly above such position, as shown in Fig. 4, by means of a rocker 40 carried by a transversely disposed shaft 41, the outer end of such rocker being disposed to engage the lower projecting end 5 of the shaft extension 36 on which the pivotal gear 35 is mounted, as described above. Projecting from shaft 41 in a direction opposite to that of rocker 40 is an arm 42, to which is attached a tension spring 43, which tends to oscillate shaft 10 44 in a clockwise direction as viewed in Figs. 3, 4 and 5, thus causing the rocker 40 to press upwardly on the lower projecting end 36 of shaft 17. The result of this action will be to lift the disc 15 into a plane where its upper face will contact with the ink distributing rollers 22 with the desired degree of pressure.

Also mounted on shaft 41 is a second arm 44 that projects therefrom in the same general direction as rocker 40 and has a loose pivotal connection at its outer end with one arm of a double arm rocker 45 oscillatorily mounted on the shaft 39. The other arm of said rocker 45 has attached thereto an oscillatory dog 46 of angular shape which carries a roller 47 and is counterweighted so as to normally rest against a pin 48 on said arm. In this position of the dog said roller 47 will be engaged by a cam 49 mounted on one of the roller frames 10 of the press when said frame is swung in a clockwise direction (see Figs. 4 and 5), and since pin 48 will prevent oscillation of dog 46 when the roller is engaged in this manner, the effect of such engagement will be to raise the end of arm 45 to which the dog is attached, depress the opposite end of said arm, and thus oscillate shaft 41 in a counterclockwise direction against spring 43 an amount sufficient to permit the shaft 17 with the inking disc carried thereby to drop until the latter approximately rests on the shaft bearing. This movement of the disc need be relatively small, i. e. only sufficient to lower the surface thereof sufficiently so that it will no longer contact with the ink transfer rollers 22.

As soon as frame 10 starts to swing in the opposite, i. e. counterclockwise direction, this being the direction of movement assumed to be taking place in Fig. 2, dog 46 is free to swing under the pressure of the engagement of cam 49 with roller 47, with the result that the corresponding arm of rocker 45 is free to drop and thus allow spring 43 again to function in the manner previously described, i. e. to raise the disc again into roller contacting position.

The location and extent of cam 49 is preferably such that the lowering of the disc 16 out-of-roller-contacting position will occur during an intermediate portion of the passage of said rollers downwardly across such disc following their contact with roller 21 of ink fountain 20. In other words, said rollers 22 will contact with the disc at the beginning of their downward travel across the latter, then the disc will be dropped out of contact with said rollers and will then again be raised into such contact when the rollers complete their downward travel; on the other hand, during the return movement of said rollers the disc will be retained in its raised, roller-contacting, position during the whole of their movement in this direction. Furthermore, the rotative movement imparted to the disc 16 through the bevel gears 35 and 37 will be timed so as to occur during the interval that the disc is out of contact with rollers 22. In this way a much more uniform distribution on the disc of the ink received by the rollers from the fountain is secured than has heretofore been possible, while

by rotating the disc during the period it is thus out of contact with the rollers wear and damage to the latter which might otherwise occur is avoided. Through the interconnection of the disc raising and lowering means with the oscillatory frame 10 which carries the form rollers, the operations just described will be synchronized with the operation of the press.

Since due to their composition both the transfer rollers and the form rollers tend to change in diameter due not only to wear but to aging, the provision of resilient means as described whereby the distributing disc will be pressed upwardly against said rollers as they pass there-across has the further advantage of insuring proper and uniform contact at all times and without requiring any special adjustment of such rollers in their mountings, as heretofore has been necessary.

In order to prevent seating of the disc with undue force or noise when it is lowered, the further means shown in Fig. 6 are provided, such figure illustrating details of the loose pivotal connection of rocker 45 with arm 44. Upon referring to this figure, it will be seen that such connection comprises a slot 50 in the end of said arm 44 and a roller 51 on the corresponding arm of rocker 45 that is disposed within such slot. Set screws 52, one on each side of the slot, project within the latter and have flat inner ends which provide the surfaces with which such roller engages. Accordingly, by adjusting the screws in one direction or the other the position of the roller 51 may be shifted transversely of the slot with a corresponding shift in the angular relation of the arm 44 and rocker 45. In this way the position of the disc relative to the axial shifting means may be correspondingly adjusted so that when the disc is lowered it is not quite in contact with the opposed face of the bearing in which shaft 17 is journaled.

In the modified construction illustrated in Fig. 7, the disc is mounted in the same manner as before and the same means for rotatably shifting the same are employed. However, instead of retaining the disc in its axially raised position by means of a spring it is positively held in this position by the action of a cam 55 on the swinging frame 10, this cam corresponding with cam 49 which in such previous construction serves to lower the disc. To effect this different mode of operation oscillatory shaft 41 is provided with an arm 56 that is connected by toggle links 57 with a rocker 58 mounted for oscillation about a fixed pivot 59. Also oscillatory about such pivot is a depending arm 60 equipped at its lower end with a roller 61, wherewith said cam 55 is adapted to engage. Movement of arm 60 relative to rocker 58 is limited by engagement of a pin 62 thereon in a slot 63 in said rocker.

Accordingly, when frame 10 with the cam 55 carried thereby swings in a counterclockwise direction (this being the condition illustrated in Fig. 7), the roller 61 on arm 60 will be engaged by the latter, and through engagement in turn of pin 62 with the left hand end of slot 63, the rocker will be swung in a clockwise direction so as to straighten out toggle links 57 in which condition of the latter the disc will be retained in its elevated position. However, upon reverse swinging movement of arm 10, engagement of cam 55 thereon with roller 61 will serve to swing rocker 60 in the opposite direction so as to break the toggle and allow the disc to drop under the influence of gravity.

The modified construction illustrated in Fig. 8 is designed to operate in much the same manner as that illustrated in Fig. 7 and just described above. Thus the same arrangement of arm 56 and toggle links 57 is utilized. However, rocker 65 which replaces rocker 58 is formed with a downwardly opening slot 66 in which is received a roller 67 on a plate-like member 68 which also carries a roller 69 at its lower end disposed so as to be engageable by the cam 55 on swinging frame 10. Plate 68 is loosely oscillatorily secured to the rocker 65 by means of two pins 70, 70 on the latter which engage with arcuate slots 71, 71 in the plate.

If now the arm 10 with its cam 55 is swung in a counterclockwise direction (this being the position assumed in Fig. 8) said cam will engage roller 69 and swing plate 68 so that the right hand pin 70 will engage the upper end of the corresponding slot 71, and roller 67 will engage the left side of slot 66 in rocker 65. The result will be to straighten out the toggle links 57 in which condition thereof the disc is retained in its elevated position. However, upon reverse movement of cam 55 the plate 68 will be oscillated in the opposite direction from that just described, such toggle will be broken and the disc allowed to drop under the influence of gravity, as before.

In the third modification illustrated in Fig. 9, the arm 75 on oscillatory shaft 41 has two concave curves on its under side adapted to cooperate with a roller 76 on one arm of a bell crank 77 mounted for oscillation about shaft 39. Pivotally attached to the other arm of said bell crank is a double acting counterweighted rocker 78 provided with rollers 79 and 80 that lie on opposite sides of its pivotal axis. Pins 81 on the bell crank arm serve normally to retain such rocker in the position illustrated in Fig. 8. Mounted in spaced relation, so as to lie above swing arm 10, are two rollers 82 and 83 which are so located as to be adapted respectively to engage rollers 79 and 80 on rocker 78 during swinging movement of arm 10.

In the position of the parts shown in Fig. 9 such swinging movement is assumed to be taking place in clockwise direction with the result that roller 82, carried by said arm 10, is brought into engagement with roller 79 on rocker 78. Continued movement of the arm 10 will accordingly oscillate bell crank 77 in a clockwise direction so as to move roller 76 from engagement with the end of arm 75 into the curved lower face thereof, thus allowing said arm to swing in a counterclockwise direction and correspondingly lower the disc. On the reverse swinging movement of arm 10 engagement of roller 82 with roller 79 on the rocker will be without effect; however, roller 83 will effectively engage the roller 80 on said rocker to swing the bell crank 77 in a clockwise direction and thus restore the parts to the positions illustrated in Fig. 8 where the disc is held in its elevated position.

Finally, Fig. 10 illustrates still another modified construction in which, as in the one shown in Figs. 1 to 5, a spring is utilized to retain the disc in its elevated position; however, in this modification a compression instead of a tension spring is utilized. Since, except for the change in the spring, the other parts are identical with such first described construction, they bear the same reference numerals in Fig. 10 as in Figs. 1 to 5 inc. However, in place of horizontal arm 75 42 to which tension spring 43 is connected, a

downwardly projecting arm 85 is attached to oscillatory shaft 41, and between the lower end of such arm and a fixed point on the press frame a compression spring 86 is interposed. The latter is held in place by means of a rod 87, one end of which slidably engages in a slot 88 in said arm while the other end passes through an eye-bolt 89 on the machine frame. Such first end of the rod furthermore has threaded thereon two nuts 90 and 91, the first of which serves as an adjustable abutment with which the arm 85 contacts, while the second serves to adjust the normal degree of compression of spring 86. By proper setting of these nuts on the rod 87, the latter will hold the disc in raised position with whatever degree of pressure is desired it should exert against the rollers passing over the disc.

In each of the several forms of the invention described above it will be seen that the operation of the disc raising and lowering means is synchronized with the press cycle with the result that the inking disc will be dropped out of contact with the ink distributing rollers at a predetermined stage in each successive printing operation. As indicated, said disc will be desirably thus dropped so as to be out of contact with said rollers during the latter portion of their downward travel and the disc will then be raised so as again to contact with said rollers as they start on their return movement. Rotation of the disc is likewise synchronized with the press cycle, since rotation of the shaft 38 is tied in with such operation, as fully described in the cited Johnson et al. Patent No. 2,079,172. It is thus rendered possible to time the dropping of the disc out of contact with the ink distributing rollers to occur during the interval when the disc is being rotated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In inking mechanism for printing presses, the combination of a shiftable ink-distributing plate, a roller movable across said plate in a plane parallel with the surface thereof, means normally pressing said plate toward said roller, whereby the latter contacts such surface, means adapted automatically to lower said plate out of contact with said roller, and means regulating said plate lowering means effective to time such lowering of said plate during a portion only of such travel of said roller thereacross, whereupon said plate may be freely shifted.

2. In inking mechanism for printing presses, the combination of a shiftable ink-distributing plate, a roller movable across said plate in a plane parallel with the surface thereof, resilient means normally pressing said plate toward said roller, whereby the latter contacts such surface, means adapted automatically to lower said plate out of contact with said roller, and means regulating said plate lowering means effective to time such lowering of said plate during a portion only of such travel of said roller thereacross, whereupon said plate may be freely shifted.

3. In inking mechanism for printing presses, the combination of a shiftable, ink-distributing plate, a roller movable across said plate in a plane parallel with the surface thereof, resilient

means normally urging said plate upwardly toward said roller, whereby the latter is adapted to contact such surface, and a member operating in synchronism with the press cycle adapted to render said resilient means ineffective and thereby drop said plate out of contact with said roller during a portion only of the latter's travel across said plate, whereupon said plate may be freely shifted.

10. 4. In inking mechanism for printing presses, the combination of a suitable bearing, an inking disc having a stud shaft journaled in said bearing, the lower end of said shaft projecting through the latter, a roller movable across said disc in a plane parallel with the face thereof, an oscillatory arm engaging such projecting shaft-end adapted to raise and lower the same together with said disc, resilient means normally actuating said arm to raise said disc, and a member operating in synchronism with the press cycle adapted to actuate said arm against said resilient means to lower said disc.

25. 5. In inking mechanism for printing presses, the combination of a suitable bearing, an inking disc having a stud shaft journaled in said bearing, the lower end of said shaft projecting through the latter, a roller movable across said disc in a plane parallel with the face thereof, an oscillatory arm engaging such projecting shaft-end adapted to raise and lower the same together with said disc, resilient means normally actuating said arm to raise said disc, a rocker connected with said arm and adapted to actuate the same against said resilient means, a dog on 30. 35. said rocker, and a cam operating in synchronism with the press cycle adapted when moving in one direction to engage said dog and thereby operate said rocker.

40. 6. In inking mechanism for printing presses, the combination of a suitable bearing, an inking disc having a stud shaft journaled in said bearing, the lower end of said shaft projecting through the latter, a roller movable across said disc in a plane parallel with the face thereof, an oscillatory arm engaging such projecting shaft-end adapted to raise and lower the same together with said disc, resilient means normally actuating said arm to raise said disc, a rocker connected with said arm and adapted to actuate the same against said resilient means, a dog on 45. 50. 55. said rocker, the connections between said rocker and arm being adjustable, and a member operating in synchronism with the press cycle adapted to actuate said arm against said resilient means to lower said disc.

7. In inking mechanism for printing presses, the combination of a suitable bearing, an inking disc having a stud shaft journaled in said bearing, the lower end of said shaft projecting through the latter, a roller movable across said disc in a plane parallel with the face thereof, an oscillatory arm engaging such projecting shaft-end adapted to raise and lower the same together with said disc, a tension spring normally actuating said arm to raise said disc, and a member operating in synchronism with the press cycle adapted to actuate said arm against said spring to lower said disc.

8. In inking mechanism for printing presses, the combination of a suitable bearing, and inking disc having a stud shaft journaled in said bearing, the lower end of said shaft projecting through the latter, a roller movable across said disc in a plane parallel with the face thereof,

an oscillatory arm engaging such projecting shaft-end adapted to raise and lower the same together with said disc, a compression spring normally actuating said arm to raise said disc, and a member operating in synchronism with the press cycle adapted to actuate said arm against said spring to lower said disc.

9. In inking mechanism for printing presses, the combination of a suitable bearing, an inking disc having a stud shaft journaled in said bearing, the lower end of said shaft projecting through the latter, a roller movable across said disc in a plane parallel with the face thereof, an oscillatory arm engaging such projecting shaft-end adapted to raise and lower the same together with said disc, a compression spring normally actuating said arm to raise said disc, and a member operating in synchronism with the press cycle adapted to actuate said arm against said spring to lower said disc, the degree of compression of said spring being adjustable.

10. In inking mechanism for printing presses, the combination of a rotatable inking disc, an ink distributing roller movable thereacross in contact with the surface of said disc, a form roller movable across the surface of said disc, means operative automatically to lower said disc out of contact with said ink distributing roller, means rendering said disc lowering means effective during a portion only of the travel of said ink distributing roller thereacross, means operative to maintain said disc in elevated position to engage said form roller during the entire movement of said form roller thereacross, and means operative to rotate said disc while thus lowered from engagement with said ink distributing roller.

11. In inking mechanism for printing presses, the combination of a shiftable ink-distributing plate, a roller movable thereacross in contact with said plate, means adapted automatically to lower said plate out of contact with said roller, means rendering said plate lowering means ef-

fective during a portion only of the travel of said roller thereacross, and means operative to shift said plate while said plate is thus out of contact with said roller.

5 12. In inking mechanism for printing presses, the combination of an ink fountain, a rotatable ink-distributing disc adjacent said fountain, an inking roller movable thereacross in rolling contact therewith toward and away from said fountain, means adapted to lower said disc out of contact with said roller, means regulating said disc lowering means effective to time such lowering of said disc to take place during the latter portion of a traverse of said disc by said roller in a direction away from said fountain, with said disc again contacting said roller at the conclusion of such traverse and throughout the return traverse of said disc by said roller toward said fountain, and means operative to rotate said disc while said disc is thus out of contact with said roller.

20 13. In inking mechanism for printing presses, the combination of a rotatable inking disc, an inking roller transversely movable thereacross in contact therewith, means adapted automatically to lower said disc out of contact with said roller, means regulating said disc lowering means effective to time such lowering of said disc during a portion only of the travel of said roller thereacross, and means operative to rotate said disc in synchronism with the press cycle while said disc is thus out of contact with said roller.
